UNITED STATES PATENT OFFICE.

WALTER HARVEY ZACHRY, OF ATLANTA, GEORGIA.

MOP.

Original application filed October 3, 1921, Serial No. 505,048. Divided and this application filed June 28, 1923. Serial No. 570,760.

To all whom it may concern:

Be it known that I, WALTER HARVEY ZACHRY, a citizen of the United States, and a resident of Atlanta, in the county of Fulton and State of Georgia, have invented certain new and useful Improvements in Mops, of which the following is a specification.

This invention relates to mops and is a division of my co-pending application 10 Serial No. 505,048 filed October 3rd, 1921.

An important object of this invention is to provide a mop having novel means whereby the same may be held in an adjusted position with relation to the handle so that 15 the operator will not be annoyed by the free swinging of the head with relation to the handle when moving the mop over the floor for cleaning purposes.

Further the invention aims to provide a 20 mop having a cleaning element which may be readily and conveniently detached for the purpose of reversing the same or for the purpose of entirely renewing the same.

Also a further object of the invention is 25 to provide a mop which is efficient, and simple to operate and cheap to manufacture.

Other objects and advantages of the invention will be apparent during the course 30 of the following description.

In the accompanying drawing, forming a part of this application and in which like numerals are employed to designate like parts throughout the same,

Figure 1 is a fragmentary perspective of 35 the mop.

Figure 2 is a vertical transverse sectional view through the cleaning element.

Figure 3 is a detailed sectional view illustrating the means for connecting the 40 shank of the mop head to the handle.

Figure 4 is a fragmentary plan view of the mop, the view illustrating the means for connecting the head or shank shown in Figure 4 to the frame of the mop.

In the drawing the frame which is generally designated by the numeral 34 is formed from spring metal bent intermediate its ends as indicated at 35 to provide a pair of slightly diverging sides 36. The sides 36 of 45 the frame 34 have their terminal portions extended laterally to provide arms 37.

It will be observed that a shank 38 is formed at its forward end with an opening to receive the bolt or cross piece 39 extended 50 through the rear portions of the sides 36

and held in position by means of nuts 40. Washers 41 are confined between the forward ends of the shank 38 and the inner sides of the portions 36 and permit the shank 38 to be adjusted with relation to the same. A second set of annular washers 42 are confined between the sides 36 and split washers 44 held on the member 39 by means of the nuts 40. The nuts 40 are not made extremely tight on the member 39 but are sufficiently loose to permit the same to be adjusted by hand. Suitable retaining devices 45 are extended through the cross piece 39 to hold the nuts 40 in position.

The cleaning element 20 is secured to the frame 34 by means of snap fasteners consisting of the coacting sections. In applying the cleaning element, the same is applied to the outer side of the frame 34 so as to enclose the frame and thereby prevent the same from scratching or marring woodwork.

The means employed for connecting the shank of the device to the handle 50 consists of a thumb screw 51 extended through a ferrule 52 and having threaded engagement with a nut 53 held within a socket in the handle by means of the ferrule. With reference to Figure 3 it will be noted that the thumb screw 51 is adapted to extend through the forward portion of the handle 80 and engages the shank whereby to detachably connect the same to the handle.

A mop constructed in accordance with this invention is convenient to use and is securely held in an adjusted position. However, 90 when it is desired to change the angle of the frame and cleaning element with relation to the handle it is merely necessary to hold the same and then swing the handle to the desired angle.

In carrying out the invention a cleaning element may be secured to the mop head by means of bolts and washers or by other suitable means which may be found adapted to the purpose.

Also fibre or bristles or other material fastened together by stitching, gluing or otherwise may be employed in lieu of the specific cleaning element illustrated in the drawing. Further the inventive idea may 105 be involved in a floor sweep as well as a mop.

Particular attention is directed to the fact that the nut 40, the bolt 39 and the washers 41 and 42 are all located within the plane of the cleaning element 20 so that the bolt, etc. 110

cannot mar the object being cleaned. This allows the mop to be used more freely and without the possibility of damaging the furniture.

5 Having thus described my invention what I claim is:—

A mop comprising a length of spring metal bent intermediate its ends to define a pair of slightly diverging spring sides, the 10 rear portions of which are extended outwardly to define branches, said spring sides being formed with aligned openings, between their upper and lower edges, a shank having a transverse bolt extending through

said openings, washers mounted on said bolt 15 and flatly engaging opposite surfaces of said spring sides, nuts threaded on opposite ends of said bolts and tightly engaging said washers with said shank and said sides, whereby said length of spring metal is held 20 in a set position and a cleaning element detachably applied to the outer surfaces of said sides and the rear surfaces of said branches, said cleaning element being in the plane of said bolt, and washers and nuts to 25 prevent destructive contact of the last named part with the objects being cleaned

WALTER HARVEY ZACHRY.
